UNITED STATES PATENT OFFICE

ROBERT WALTER CAMMACK, OF MOUNT VERNON, NEW YORK

DENTAL FLOSS HOLDER

Application filed January 4, 1932. Serial No. 584,675.

This invention relates to dental floss holders designed to hold a strand of dental floss taut and in a convenient manner to be easily inserted between the teeth for removing any particles of food or the like which may be lodged between them.

The object of this invention is to provide an improved floss holder and especially to an improved means for cutting off the used floss.

Another object is to provide a cut-off which is conveniently located and due to its structure and location will not collect any foreign material and will in no way injure the hand or mouth when being used.

Referring to the accompanying drawing which is made a part hereof and on which similar reference characters indicate similar parts,

Figure 1 is a sectional view in elevation of the holder,

Figure 2, an enlarged perspective view of the head showing the cut-off in position,

Figure 3, a view in elevation of the inner end of the head, showing the cut-off mounted thereon,

Figure 4, a top view of the cut-off and a portion of the head of the holder, and

Figure 5, substantially a section on line 5-5 of Figure 3. In the drawing reference character 10 indicates a hollow handle which serves as a magazine for a coil of dental floss and is provided with a closure cap or plug 11 fitted on one end. The other end of the handle is provided with a reduced externally threaded ferrule 12 adapted to engage a threaded socket 13 in the head 14. The ferrule 12 is provided with a groove or notch 31 formed adjacent the handle 10 as clearly shown in Figure 5 and for a purpose which will be later described. The head 14 is provided with spaced prongs 15 and 16 across the extremities of which a strand of floss 17 is stretched. The head 14 is further provided with a passage 18 extending from the bottom of the socket 13 to the forward end of the head and connects with a similar passage 19 in the prong 15 and which is substantially perpendicular thereto.

The inner portion of the extremity of the

prong 15 is notched at 20 and is in alignment with a groove 21 in the extremity of the prong 16 in order to hold a strand of floss in proper position when stretched across them. The cut-off 22 is secured by a prong 55 or similar device 23 to the inner end of the head 14. The cut-off 23 is in the form of a lock washer split at 24 and formed of any suitable metal but preferably of stainless spring steel. The edges of the cut-off are 60 flush or may be slightly countersunk with respect to the head and the handle to prevent any danger of cutting the hand or mouth when the device is being used. A portion 25 of the circumference of the cut-off is cut 65 and turned in a manner to provide a lip 26 which seats in a recess 27 in the head 14. The tip of this turned portion is cut away as clearly shown in Figure 4 at 28.

This operation forms cutting edges 29 and 30 which may be sharpened and through which a strand of floss when pulled will be cut. If desired one side of the cut-off may be roughened where the floss contacts to prevent slipping.

In threading the holder, the head 14 and the cap 11 are removed from the handle and a supply of floss is placed in the handle with one end extending through the ferrule 12. The cap is then replaced. The end of the 80 floss is threaded through the passages 18 and 19 and a length sufficient to extend over the prongs is pulled out. The handle is turned into the head and the free side of the cut-off adjacent the split 24 engages in 85 the groove 31 since this portion tends to spring slightly inwardly due to its structure being of a lock-washer type as shown in Figure 3. The handle is unloosened approximately one turn, the groove 31 carries this 90 portion with it leaving a space between the cut-off and the head into which the free end of the floss may be readily inserted and guided to the cutting edges 29 and 30. The floss is then cut and the handle tightened. 95 Should it be desirable to completely separate the handle and the head, the groove 31 is so formed with a rounded edge that it will release the cut-off after traveling a short distance.

The forward end of the ferrule 12 engages the bottom of the socket binding the floss at this point and the other end is firmly held between the head and the handle thus making the floss taut across the prongs. The device is then ready for use.

Should it be desired to substitute a new length of floss after use this is accomplished by simply unloosening the handle and pulling a length sufficient to allow the used portion to clear the cut-off when replaced on the rear prong and between the cut-off and the head. The surplus is then cut off and the head is again tightened. It is not necessary to re-thread the device until the floss becomes broken or is exhausted from the handle and at no time is it necessary to touch the floss prior to its use.

This cut-off arrangement is simple in structure, positive in action and is not exposed when the device is being used, therefore it will not become soiled and will not injure the mouth or hand by cutting them as is frequently the case in other devices of this type.

It will be obvious to those skilled in the art that various changes may be made in my device without departing from the spirit of the invention and therefore I do not limit myself to what is shown in the drawing and described in the specification, but only as indicated by the appended claims.

Having thus fully described my said invention, what I claim as new and desire to secure by Letters Patent, is:

1. A dental floss holder comprising a head having spaced prongs thereon, a handle threaded into said head, a passage from said handle through said head extending to the tip of the remote prong, and means mounted at the intersection of said head and handle for severing said floss, substantially as set forth.

2. A dental floss holder comprising a head having spaced prongs thereon, a magazine handle secured to said head, a passage from said handle through said head extending through the prong remote from the handle, and shearing means mounted between said head and handle at their intersection for cutting said floss, substantially as set forth.

3. A dental floss holder comprising a head having a pair of spaced prongs, a socket in said head at the outer side of one of the prongs, the outer side of the prong adjacent said socket being relatively straight, a passage through the head from said socket to the extremity of the remote prong, a handle threaded into said socket, and shearing means positioned at the intersection of said head and said handle for cutting off the used floss, substantially as set forth.

4. A dental floss holder comprising a magazine handle, a head having a pair of prongs and a socket to receive said handle, a passage from the bottom of said socket to the ex-

tremity of the remote prong whereby floss may be threaded from the handle through the head across the prongs and secured between said head and said handle, and a cut-off positioned between the inner ends of said head and said handle for cutting said floss, substantially as set forth.

5. In combination with a dental floss holder having a magazine handle and a channeled head of a cut-off mounted between said handle and said head comprising a flat washer provided with a securing element thereon and a notched circumference forming a pair of cutting edges for severing a strand of floss when placed between them, substantially as set forth.

6. In combination with a dental floss holder having a handle and a head of a cut-off positioned intermediate said handle and head comprising a flat split washer having a notched circumference forming a pair of cutting edges, the free ends at the split portion being adapted to spring apart when the head and handle are loosened to permit insertion of the floss and serve as a guide for the floss to the cutting edges, substantially as set forth.

7. A dental floss holder comprising a magazine handle, a head having a pair of prongs and a socket to receive said handle, a passage from the bottom of said socket to the extremity of the remote prong whereby floss may be threaded from the handle through the head across the prongs and secured between said head and said handle, a cut-off positioned between said head and said handle for cutting said floss, and means on said handle adapted to engage and to separate said cut-off from said head as the handle is loosened in the socket, substantially as set forth.

8. A dental floss holder comprising a handle having a reduced end and a groove formed at the junction thereof, a head having a pair of prongs and a socket to receive said reduced end of the handle, a passage from the bottom of said socket to the extremity of the remote prong whereby floss may be threaded from the handle through the head across the prongs and secured between said head and said handle for cutting said floss, said cut-off adapted to engage in said groove as the handle is loosened in the socket thereby separating said cut-off from said head, substantially as set forth.

In witness whereof, I have hereunto set my hand at Mt. Vernon, New York, this twenty-second day of December, A. D. nineteen hundred and thirty-one.

ROBERT WALTER CAMMACK.
